REEL ROD FOR A PRINTING CYLINDER

Isidor Tornberg, Plainfield, N. J., assignor to
Wood Newspaper Machinery Corporation, New
York, N. Y., a corporation of Virginia

Application May 18, 1936, Serial No. 80,295

1 Claim. (Cl. 242—74)

The principal objects of this invention are to provide a reel rod for an impression cylinder, or the like, which can be manipulated to enable it to grasp the end of the blanket or draw sheet in a very simple manner; to provide means whereby the blanket or draw sheet can be reeled in either direction; to provide a split reel rod, one part of which occupies most of the rod and is rotatably mounted in the printing cylinder and the other part of which is detachably connected with the first; to provide yielding means for holding the two parts together; to provide the two parts of the reel rod of unequal segments held together by springs constituting substantially a complete circle, but cut to permit insertion of the end of the blanket or draw sheet; to provide the two segments of the reel rod on adjacent faces with slanting surfaces to permit a tool to be inserted for spreading them apart to permit the insertion of the end of the blanket; to provide means whereby the blanket, if wound in a skewed position, can be rendered straight by moving one end of the reel rod in whatever direction is required by means, preferably, of an eccentric adjustable bushing in one end of the rod.

Other objects and advantages of the invention will appear hereinafter.

Reference is to be had to the accompanying drawings which show a preferred embodiment of this invention.

Fig. 1 is a side elevation of part of an impression cylinder of a printing press with a preferred embodiment of this invention applied thereto.

Fig. 2 is a sectional view on the line 2—2 of Fig. 1.

Fig. 3 is an end view of the operating mechanism.

Fig. 4 is a cross section of the two part reel rod showing it closed.

Fig. 5 is a similar view with the two parts pried open, and Figs. 6 and 7 are details of the eccentric bushing.

The impression cylinder of a printing press is commonly covered with packing in order that the printing may be made clear and distinct. The usual type of packing or covering is applied by hanging one end of the covering over pins or clamping means and reeling up the other end on a reel rod. This invention relates mainly to that reel rod.

It is difficult to place the reeled up end of a blanket or draw sheet squarely so that it will be drawn up with equal tightness on both edges; moreover, sometimes the blanket itself is not en-

tirely symmetrical and, in any case, it is difficult to attach the blanket or draw sheet to the reel rod in a sufficiently square manner to enable the sheet or blanket, when drawn firmly over the surfaces of the cylinder, to lie firmly at all points against the impression cylinder. If it does not it will cause defects in printing. This invention is designed to overcome these difficulties in two particulars; the first is to provide a means for inserting the forward end of the blanket in a reasonably square and accurate position; the second is to change the position of the end of the forward operating reel rod to take out the skew of the blanket.

The printing cylinder 1 carries a reel rod 2 loosely mounted at one end, in a hole 3, the other end being mounted in a rotatable eccentric bushing 4. The eccentric bushing 4 has a flange on its lefthand end, as viewed in Fig. 1, and is mounted in an end plate 5 which latter is secured to this cylinder 1 by screws 6. A worm wheel 8 is secured to the bushing 4 and, in cooperation with the flange mentioned above, holds the bushing 4 against end motion. The worm wheel 8 is secured to the eccentric bushing 4 and meshes with a worm 9 carried in a hole 10 of the cylinder 1 and a poppet 11 secured to the end plate 5. A collar 12 is pinned to the worm 9. As viewed in Fig. 3 a non-circular member 13 is provided for rotating the worm 9.

It is apparent that, by rotation of this worm, the eccentric bushing 4 may be rotated to throw the end of the reel rod 2 out of alignment with the axis of the cylinder 1. This action may be used to correct any looseness in the draw sheet 14 which is wrapped around the reel rod 2.

A hub 15 of the poppet 11 is provided for the mounting of a pawl 16, a washer 17 and appropriate screw holding the pawl in place. The pawl 16 cooperates with a ratchet wheel 18 carried on a non-circular member 19 of the reel rod 2. A pin 20 serves to keep the ratchet wheel 18 in place on the non-circular member.

An oppositely disposed pawl 21 mounted by a poppet 22 on the end plate 5 is furnished to permit the draw sheet 14 to be operated in a counterclockwise direction as viewed in Fig. 3. When this action is desired the pin 20 is removed and the ratchet 18 reversed so that it will cooperate with the pawl 21.

The reel rod 2 is of segmental shape to cooperate with a reel rod segment 23 the two being held together by circular springs 24 cut at points 25. The reel rod 2 and reel segment 23 are recessed at 39, as shown in Fig. 1, to accommodate

- the circular springs 24. A series of these springs is placed around the reel rod 2, and segment 23, in this recess in accordance with the amount of tension desired. Oppositely slanting surfaces 26 5 are provided on the adjacent surfaces of the reel rod 2 and reel segment 23 so that a screw driver, or similar shaped tool, can be inserted for opening these parts according to Fig. 5, allowing a draw sheet or blanket to be entered therein.
- 10 With the removal of the screw driver, the springs 24 clamp the blanket or draw sheet between the main reel rod 2 and the reel segment 23.

The other end of the draw sheet or blanket can be placed over blanket pins 27 or be held 15 by tympan clamp fingers 28 carried on a tympan rod 29 journaled in a hole 30 of the cylinder 1 and end plate 5. These tympan clamp fingers 28 are riveted to the tympan rod 29 by rivets 31. An arm 32 is secured to the end of the tympan 20 rod 29 and has its free end bifurcated to accommodate an eye-bolt 33. One end of the eye-bolt is pivoted by a stud 34 on the end plate 5, and the other end carries a half round pin 35 co- 25 operating with a complementary surface of the arm 32. A nut 36, in cooperation with the half round pin 35, can be used to force the arm 32 and tympan rod 29 in a clockwise direction as

shown in Fig. 3. This presses the tympan clamp fingers 28 against a surface 37 of the cylinder 1 to thereby clamp the draw sheet or blanket. Tympan clamp pins 38 are provided, entering holes in the tympan clamping fingers 28, to assist 5 in holding the draw sheet or blanket.

It is thus apparent that a new and useful device is provided for easily securing the free end of a blanket or draw sheet to a reel rod and means are provided for throwing the reel rod 10 out of alignment with the axis of the printing cylinder to insure the draw sheet or blanket being held firmly against the surface of the impression cylinder.

Having thus described my invention and the 15 advantages thereof, I do not wish to be limited to the details herein disclosed, otherwise than as set forth in the claim, but what I claim is:

A reel rod formed of two segments, the adjacent surfaces of said segments at one side being 20 slanted away from each other across the rod to form an opening for the insertion of a tool to permit them to be separated, and a series of springs surrounding it and yieldingly holding the parts against separation. 25

ISIDOR TORNBERG.
